Attorney

UNITED STATES PATENT OFFICE.

DAVID F. VAUGHAN, OF RIVERTON, NEW JERSEY.

ANTICREEPER FOR RAILROAD-RAILS.

1,180,890.

Specification of Letters Patent. Patented Apr. 25, 1916.

Application filed October 1, 1915. Serial No. 53,501.

To all whom it may concern:

Be it known that I, DAVID F. VAUGHAN, a citizen of the United States, residing at Riverton, in the county of Burlington and 5 State of New Jersey, have invented certain new and useful Improvements in Anti-creepers for Railroad-Rails, of which the following is a specification.

My invention relates to improvements in 10 anticreepers for railroad rails, which are adapted to grip the rails and engage a stationary part of the road bed and prevent the forward, longitudinal displacement or the creeping of the rails.

15 The object of my invention is to provide an anticreeper of novel, simple, inexpensive and efficient construction adapted to grip a rail base, and held in gripping engagement with the rail base and in constant readiness 20 for action under all conditions by the action of a suitable spring associated with the parts of the anticreeper and the rail in a novel manner to effect the desired result.

With this object in view the invention 25 consists of the elements and the combinations of them hereinafter fully described and claimed.

In the accompanying drawings, illustrating my invention: Figure 1 is a plan view 30 of a portion of a railroad rail, a portion of a cross-tie supporting the same and my improved anticreeper applied to the rail. Fig. 2 is a side elevation of the parts shown in Fig. 1. Fig. 3 is a transverse section 35 through the rail, on line 3-3 of Fig. 2. Fig. 4 is a transverse section through the rail and the anticreeper, on line 4-4 of Fig. 2. Fig. 5 is a perspective view of the spring.

40 Referring to the drawings, 2 designates a portion of a railroad cross-tie and 5 a railroad rail of usual construction. The cross-tie 2 forms a stationary part of the road bed which supports the rail 5, and 45 over which the rail tends to creep under the well known conditions.

My improved anticreeper is supported by the rail base 6 and is of the following construction: Extending beneath the rail base 50 6 is a member or bar 7 having a hook or

jaw formed on one end thereof which is hooked over and which engages one side of the rail base 6, as shown. The other end of the bar 7 is provided with an upwardly extending arm 9 which is adapted to engage 55 the side of the rail base 6 opposite to the side thereof engaged by the jaw 8 and prevent outward movement of the jaw from the rail base, when the parts are in the position shown in the drawings.

60 The arm is provided with an opening 10 into which is inserted the outwardly projecting arm 11 of a keeper 12 which rests against the inner face of the arm 9 and extends over the adjacent side of the rail 65 base 6 and engages the top thereof and prevents downward movement of the end of the bar 7 carrying the arm 9. The arm 11 of the keeper 12 is provided with a shoulder 11^a which is adapted to engage the adjacent edge of the rail base 6 and prevent displacement of the keeper 12 from the arm 9 when the parts are in the position shown in the drawings. When it is desired to remove the anticreeper from the rail, the end 75 of the bar 7 carrying the arm 9 is raised so that the shoulder 11^a clears the edge of the rail base 6. The arm 11 is then withdrawn from the opening 10, and the end 80 of the bar 7 carrying the arm 9 is then lowered until the arm 9 is below the plane of the bottom of the rail 5. The jaw 8 may then be moved outwardly from the rail base. The anticreeper may be applied to the rail 85 by a reversal of the operation just described.

The top of the bar 7 is provided with a depression 13 therein in which is placed a suitable spring 14, preferably helical in form, as shown. Normally the spring 14, 90 rests upon the bottom of the depression 13 and the upper end of the spring extends above the top of the bar 7 a sufficient distance to cause the spring 14 to be compressed when the anticreeper is applied to 95 the rail, so that, after the anticreeper has been applied to the rail, the spring 14 will force the bar 7 downwardly and thus force the keeper 12 and the upper part of the jaw 8 down upon the rail base 6 and serve 100

to firmly hold the anticreeper in gripping engagement with the rail and in constant readiness for action under all conditions.

Projecting forwardly from the bar 7, or in the direction in which the rail tends to creep, as shown by the arrow, is an arm 15 provided with an abutment 16 on its forward end which is adapted to engage the cross-tie 2 and prevent the rail from creeping. The abutment portion 16 of the anticreeper is preferably located adjacent to one end of the bar 7 so that the other end of the bar 7 will be maintained out of contact with the cross-tie 2. Should the rail 5 attempt to creep forwardly, the abutment 16 will engage the cross-tie 2 and prevent forward movement of the end of the bar 7 carrying the abutment 16, while the rail 5 will carry the other end of the bar 7 forwardly; and, immediately upon the initial creeping movement of the rail 5, the bar 7 will tend to assume a diagonal position beneath the rail 5, forcing the arm 9 and the wall 17 of the jaw 8 inwardly against the respective sides of the rail base 6, thus causing the anticreeper to increase its grip upon the rail.

I preferably provide the wall 17 with outwardly diverging faces, as shown in Fig. 1, which meet in a central bearing which engages the side of the rail base 6 to bring the strain within the jaw 8 centrally of the bar 7; and I provide the wall 18 of the arm 9 which engages the side of the rail base 6 with similar outwardly diverging faces, as shown in Fig. 1, which meet in a central bearing which engages the side of the rail base to bring the strain centrally of the arm 9 and bar 7 when the anticreeper grips the rail by the action of the bar 7 in tending to assume the diagonal position, as previously explained.

The wall of the depression 13 surrounding the spring 14 prevents displacement of the spring from its operative position; and, by the novel construction hereinbefore described, I am enabled to employ the well known helical spring commonly used to hold nuts in place in railroad structures, as the spring means which maintains the anticreeper in gripping engagement with the rail, so that such springs which are used in great numbers and are available in nearly all localities along the tracks of railroads may always be at hand for use in connection with my improved anticreeper.

I claim:

1. The combination with a railroad rail having a base, and a stationary part of a road bed, of an anticreeper adapted to engage said stationary part and comprising two connected parts which are separable one from the other, one part extending beneath the rail base and the other part extending over the rail base, and a spring interposed

between one of said parts and the rail base 65 and pressing one of said parts toward the rail base and pressing the other of said parts away from the rail base and holding the anticreeper in gripping engagement with the rail.

2. The combination with a railroad rail having a base, and a stationary part of a road bed, of an anticreeper adapted to engage said stationary part and comprising a member provided with a jaw having a part 70 extending beneath the rail base and a part extending over the rail base, said jaw being removable outwardly from the rail base and said member being provided with means preventing outward movement of the jaw from the rail base, and a spring interposed between one of said parts and the rail base and pressing one of said parts toward the rail base and pressing the other of said parts away from the rail base and holding the 75 anticreeper in gripping engagement with the rail.

3. The combination with a railroad rail having a base, and a stationary part of a road bed, of an anticreeper adapted to engage said stationary part and comprising two connected parts, one part extending beneath the rail base and the other part extending over the rail base, and a helical spring interposed between one of said parts 80 and the rail base and pressing one of said parts toward the rail base and pressing the other of said parts away from the rail base and holding the 85 anticreeper in gripping engagement with the rail, said anticreeper being provided with means preventing displacement of said spring.

4. The combination with a railroad rail having a base, and a stationary part of a road bed, of an anticreeper adapted to engage said stationary part and comprising a member provided with a jaw having a part 90 extending beneath the rail base and a part extending over the rail base, said jaw being removable outwardly from the rail base and said member being provided with means preventing outward movement of the jaw from the rail base, and a helical spring interposed 95 between one of said parts and the rail base and pressing one of said parts toward the rail base and pressing the other of said parts away from the rail base and holding the anticreeper in gripping engagement with the rail, said anticreeper being provided with means preventing displacement of said spring.

5. The combination with a railroad rail having a base, and a stationary part of a road bed, of an anticreeper adapted to engage said stationary part and comprising a 100 bar extending transversely beneath the rail and provided with parts on the end portions thereof engaging the respective side portions

- of the rail base, and a helical spring exerting pressure against the rail in one direction and against a part of the anticreeper in the reverse direction and holding the anticreeper in gripping engagement with the rail, said anticreeper being provided with means preventing displacement of said spring.
6. The combination with a railroad rail having a base, and a stationary part of a road bed, of an anticreeper adapted to engage said stationary part and comprising two connected parts, one part extending beneath the rail base, the other part extending over the rail base and one part having a socket formed therein, and a spring inserted into said socket and interposed between one of said parts and the rail base and pressing one of said parts toward the rail base and pressing the other of said parts away from the rail base and holding the anticreeper in gripping engagement with the rail.
7. The combination with a railroad rail having a base, and a stationary part of a road bed, of an anticreeper adapted to engage said stationary part and comprising a bar extending beneath the rail and having a jaw on one end thereof embracing one side of the rail base, said bar having an arm extending upwardly from the other end thereof and adapted to engage the other side of the rail base and prevent outward movement of the jaw from the rail base, said arm permitting free vertical movement of the adjacent end of the bar while the jaw is engaged with the rail base to permit the application of the anticreeper to and its removal from the rail base, a removable keeper engaging said arm and the top of the rail base and preventing downward movement of said arm and bar, and a spring inserted into said socket and forcing said keeper down upon the rail base and holding the anticreeper in gripping engagement with the rail.
8. The combination with a railroad rail having a base, and a stationary part of a road bed, of an anticreeper adapted to engage said stationary part and comprising a bar extending beneath the rail and having a jaw on one end thereof embracing one side of the rail base, said bar having an arm extending upwardly from the other end thereof and adapted to engage the other side of the rail base and prevent outward movement of the jaw from the rail base, said arm having an opening therein and permitting free vertical movement of the adjacent end of the bar while the jaw is engaged with the rail base to permit the application of the anticreeper to and its removal from the rail base, and a removable keeper inserted into said opening and engaging the top of the rail base and preventing downward movement of said arm and bar, and a spring inserted into said socket and forcing said keeper down upon the rail base and holding the anticreeper in gripping engagement with the rail.
9. The combination with a railroad rail having a base, and a stationary part of a road bed, of an anticreeper adapted to engage said stationary part and comprising a bar extending beneath the rail and having a jaw on one end thereof embracing one side of the rail base, said bar having an arm extending upwardly from the other end thereof and adapted to engage the other side of the rail base and prevent outward movement of the jaw from the rail base, said arm permitting free vertical movement of the adjacent end of the bar while the jaw is engaged with the rail base to permit the application of the anticreeper to and its removal from the rail base, a removable keeper engaging said arm and the top of the rail base and preventing downward movement of said arm and bar, and a spring inserted into said socket and forcing said keeper down upon the rail base and holding the anticreeper in gripping engagement with the rail.
10. The combination with a railroad rail having a base, and a stationary part of a road bed, of an anticreeper adapted to engage said stationary part and comprising a bar extending beneath the rail and having a jaw on one end thereof embracing one side of the rail base, said bar having an arm extending upwardly from the other end thereof and adapted to engage the other side of the rail base and prevent outward movement of the jaw from the rail base, said arm having an opening therein and permitting free vertical movement of the adjacent end of the bar while the jaw is engaged with the rail base to permit the application of the anticreeper to and its removal from the rail base, a removable keeper inserted into said opening and engaging the top of the rail base and preventing downward movement of said arm and bar, and a spring inserted into said socket and forcing said keeper down upon the rail base and holding the anticreeper in gripping engagement with the rail.
11. The combination with a railroad rail having a base, and a stationary part of a road bed, of an anticreeper adapted to engage said stationary part and comprising a bar extending beneath the rail and having a jaw on one end thereof embracing one side of the rail base, said bar having an arm extending upwardly from the other end thereof and adapted to engage the other side of the rail base and prevent outward movement of the jaw from the rail base, said arm having an opening therein and permitting free vertical movement of the adjacent end of the bar while the jaw is engaged with the rail base to permit the application of the anticreeper to and its removal from the rail base, a removable keeper inserted into said opening and engaging the top of the rail base and preventing downward movement of said arm and bar, and a spring inserted into said socket and forcing said keeper down upon the rail base and holding the anticreeper in gripping engagement with the rail.

jacent end of the bar while the jaw is engaged with the rail base to permit the application of the anticreeper to and its removal from the rail base, and a removable keeper 5 inserted into said opening and engaging the top of the rail base and preventing downward movement of said arm and bar, said keeper having a shoulder adapted to engage a part of the structure and prevent dis-

placement of said arm from said opening, 10 and said anticreeper having a spring part forcing said keeper down upon the rail base and holding the anticreeper in gripping engagement with the rail.

In testimony whereof I affix my signature 15 hereto.

DAVID F. VAUGHAN.
